(57) **CLAIM**

The ornamental design for a ceiling fan mount, as shown and described.

DESCRIPTION

FIG. 1 is a top perspective view of a ceiling fan mount showing our new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top perspective view of FIG. 1 shown in an alternate environment;

FIG. 10 is a bottom perspective view of FIG. 9;

FIG. 11 is a front elevational view of FIG. 9;

FIG. 12 is a rear elevational view of FIG. 9;

FIG. 13 is a left side elevational view of FIG. 9;

FIG. 14 is a right side elevational view of FIG. 9;

FIG. 15 is a top plan view of FIG. 9;

FIG. 16 is a bottom plan view of FIG. 9;

FIG. 17 is a top perspective view of FIG. 1 shown in a second alternate environment;

FIG. 18 is a bottom perspective view of FIG. 17;

FIG. 19 is a front elevational view of FIG. 17;

FIG. 20 is a rear elevational view of FIG. 17;

FIG. 21 is a left side elevational view of FIG. 17;

FIG. 22 is a right side elevational view of FIG. 17;

FIG. 23 is a top plan view of FIG. 17;

FIG. 24 is a bottom plan view of FIG. 17;

FIG. 25 is a top perspective view of FIG. 1 shown in a third alternate environment;

FIG. 26 is a bottom perspective view of FIG. 25;

FIG. 27 is a front elevational view of FIG. 25;

FIG. 28 is a rear elevational view of FIG. 25;

FIG. 29 is a left side elevational view of FIG. 25;

FIG. 30 is a right side elevational view of FIG. 25;

FIG. 31 is a top plan view of FIG. 25; and,

FIG. 32 is a bottom plan view of FIG. 25.

The fan blade portions, hub components, light, and upper mount components shown in broken lines are unclaimed subject matter, and form no part of the claimed design.
